UNITED STATES PATENT OFFICE.

FRANCIS LAPLANTE, OF BOSTON, MASSACHUSETTS.

DESIGN FOR BRICK OR STONE.

SPECIFICATION forming part of Design No. 22,076, dated December 20, 1892.

Application filed November 19, 1892. Serial No. 452,585. Term of patent 14 years.

To all whom it may concern:

Be it known that I, FRANCIS LAPLANTE, a subject of the Queen of Great Britain, residing at Boston, in the county of Suffolk, State of Massachusetts, have invented and produced a new and original Design for Ornamental Brick or Stone, of which the following is a specification, reference being had to the accompanying drawings, forming part thereof.

Figure 1 of the drawings shows in perspective an ornamental brick showing my design, and Fig. 2 is a front elevation thereof.

The leading feature of my design for an ornamental brick or stone consists of an irreg-

ular face composed of two adjacent reversed 15 frusto conical surfaces *a* and *b*, springing from the opposite front edges *a'* and *b'*.

I claim—

The design for an ornamental brick, substantially as herein shown and described. 20

In testimony whereof I have signed my name to this specification in the presence of two subscribing witnesses.

FRANCIS LAPLANTE.

Witnesses:

JOHN C. EDWARDS,
FREDERICK L. EMERY.
